INSIDE LABEL AND CORNER FLAP

Filed March 15, 1927

UNITED STATES PATENT OFFICE

FRANK RODGERS NEELY, OF ALLENBROOK, PENNSYLVANIA, ASSIGNOR TO A. H. BALLIET CORPORATION, OF ALLENBROOK, PENNSYLVANIA, A CORPORATION OF PENNSYLVANIA

INSIDE LABEL AND CORNER FLAP

Application filed March 15, 1927. Serial No. 175,471.

My invention relates to the inside wrapping of cigar boxes.

A purpose of my invention is to make the flap label or labels at the lid hinge of a cigar box in one piece with an inside cover of the lid, thereby lessening the cost of electrotyping and of inside wrapping. According to the wish of the customer, I make the flap label portion of my wrap form corner flaps at opposite ends of the hinge or a middle flap at an intermediate portion of the hinge.

Further purposes will appear in the specification and claims.

I have elected to show two forms only of my invention, selecting forms that are practical and efficient in operation and that well illustrate the principles involved.

Figures 1 and 5 are top plan views of somewhat different forms of electrotyped wrap, adapted to serve respectively as an inside cover of a lid and corner flap labels, and as an inside cover of a lid and a middle flap label.

Figure 2 is a longitudinal vertical section to enlarged scale through a cigar box with lid raised and my wrap of Figure 1 applied. This corresponds to line 2-2 of Figure 3.

Figure 3 is a broken vertical, central section of Figure 2.

Figure 4 is a broken horizontal section upon the line 4-4 of Figure 3.

Figure 6 is a view corresponding to Figure 4 except that the wrap shown is that of Figure 5.

Like numerals refer to like parts in all figures.

Describing in illustration and not in limitation and referring to the drawings:

My present invention is directed chiefly toward a detail of the inside wrapping of a cigar box.

It is usual to cover the outside of the bottom and sides of the box with an electrotyped label or cover 10, which overlaps the top of the box along the sides.

In the illustration the lid 11 of the box 12 is hinged along its lower outer edge 13 by outside and inside flexible wrappings 14 and 15 which respectively comprise a strip of

muslin and a portion of the inside cover of the lid.

The strip of muslin has a lower portion 16 glued along the back of the box and an upper portion 17 glued along the rear edge of the lid and overlapping the top of the lid, and is covered by the outside lid-cover 18 which is usually lapped around the edges of the lid at front and sides at 19.

The inside cover 20 presents advertising 60 or ornamental electrotyped matter 21 on the inside of the lid.

All of the above is old in the cigar box art.

Prior to my present invention in addition to the inside lid label a flap label or flap 65 labels have been used, extending horizontally across the box over the cigars. They have been made as separate pieces and have been supported by integral vertically extending portions glued to the front walls of the back 70 of the boxes or to hinge members which are glued to these front walls. Their electrotyping has been comparatively expensive and they have been separately inserted by hand before insertion of the box lining.

I form the flap labels 23 as parts of the inside cover labels and preferably integral with them, permitting them to be electrotyped at 22 as part of the cover label and to be inserted with it.

The combined cover label and flaps are creased along the outer lower edges 13 of the lids and below the creases have a portion 24 glued over the top of the back of the box, which portions are in line with the ornamental flaps extending over the cigars. Usually the combined structure will be provided with another flap or flaps 25 or 31 glued down over the inside of the back of the box.

By thus uniting the flaps with the inside cover and gluing the interior section 24 to the upper edge of the back of the box I form the flaps as a continuation of this portion 24 and extend them into the box in the same plane without necessity for creasing them. At the same time I obtain the benefit of attachment of the sheet to the inside of the back of the box by attachment of the flap 25 to it.

As the additional cost of electrotyping the

inside lid cover and flaps together is less than the cost of electrotyping the inside cover and the separate flaps, forming the flaps integral with the inside lid label reduces the cost of 5 electrotyping.

I also save considerably in the time required for placing the flaps and can place them more accurately. In addition I avoid a line at the top of the flap appearing where it 10 was creased in the prior art form.

The inside end linings 26, front lining 27 and back lining 28 are glued along their top portions on the inside of the box and creased at 29 to extend over the bottom as in the prior 15 art.

The back lining is glued over any flap portion 25 of the inside cover of the lid and lies under the flap portion 23 of the lid-cover.

The flap portion or portions 23 of the inside 20 lid cover extend along the whole length or any desired portion or portions of the length of the box, the position or positions of the flap or flaps being variant according to fashion or variant desires of different customers.

In Figures 1 to 4 the flap portions of the inside cover of the lid form the usual corner flap labels at each end of the lid, and an intermediate portion 30 between the flaps is 30 glued down against the back, while in Figures 5 and 6 the flap label 23' is in the middle and portions 31 at each end thereof are glued down to the back.

Obviously the portions 30 or 31 glued 35 against the back will be both omitted when the flap is extended the length of the lid.

In view of my invention and disclosure, variations and modifications to meet individual whim or particular need, will doubtless 40 become evident to others skilled in the art, and I claim all such in so far as they fall within the reasonable spirit and scope of my invention.

Having thus described my invention, what 45 I claim as new and desire to secure by Letters Patent is:—

1. In a cigar box having a lid hinged to the back of the box, an inside label for the lid creased along the hinge, having an outer 50 portion beyond the crease glued to the lid, an intermediate portion inside the crease glued along the top of the back and an inner portion forming a flap label to lie above the packed cigars.

55 2. In a cigar box having a lid hinged to the back of the box, an inside integral lid label wrap creased along the hinge, having a portion beyond the crease secured to the bottom of the lid, an intermediate portion 60 inside and along the crease on the top of the back, one inner portion lapped down to the inside of the back and another inner portion forming a flap to lie above the cigars.

3. In a cigar box having a lid hinged to 65 the back of the box, an inside integral lid

label wrap creased along the hinge, having a portion beyond the crease on the bottom of the lid, an intermediate portion inside and along the crease on the top of the back and lower extensions to form respectively a lap 70 against the back and a flap to lie above the packed cigars.

4. In a cigar box having a lid hinged to the back of the box, an inside integral lid label wrap creased along the hinge, having an 75 outer portion secured to the bottom of the lid, an intermediate portion secured to the top of the back and three lower extensions to form a lap glued against the back near the middle thereof and a corner flap at each side 80 of the lap to lie above the packed cigars.

5. In combination, a box body, a cover hinged thereto, and a label member constructed and arranged to be attached to the inner face of said cover and a price tag integral 85 with said member and adapted to be disposed over the contents of the said box.

FRANK RODGERS NEELY.
